FEEDING DEVICE FOR ROCK DRILLS

William A. Morrison, Easton, Pa., assignor to Ingersoll-Rand Company, New York, N. Y., a corporation of New Jersey

Application August 14, 1948, Serial No. 44,249

3 Claims. (Cl. 255—45)

1

This invention relates to rock drills, and more particularly to a feeding device for rock drills of the reciprocatory piston type, the piston of which is fixedly secured to the working implement which it actuates.

One object of the invention is to control the descending or feeding movement of the rock drill.

Another object is to enable the resistance to descending movement of the rock drill to be conveniently and readily varied in accordance with variations in the hardness of the material being drilled.

Other objects will be in part obvious and in part pointed out hereinafter.

In the drawings accompanying this specification and in which similar reference numerals refer to similar parts,

Figure 1 is a side elevation, partly broken away, of a rock drilling mechanism equipped with a feeding device constructed in accordance with the practice of the invention.

Figure 2 is a longitudinal elevation, partly in section, of the motor and transmission elements serving to control feeding movement of the rock drill,

Figure 3 is a transverse view taken through Figure 2 on the line 3—3,

Figure 4 is an exploded view showing various parts in perspective, and

Figure 5 is a transverse view taken through Figure 2 on the line 5—5.

Referring more particularly to the drawings, the invention is shown applied to a drilling mechanism comprising a mounting 20 that supports a vertical column 21 to serve as a guide for a rock drill 22. The column 21 may, as indicated, be of the type shown in U. S. Patent No. 2,090,479 to D. W. Hart, and accordingly comprises a pair of relatively spaced bars 23 of structural shape, the legs 24 of which serve as guides for a saddle 25 carrying the rock drill 22.

The saddle 25 is slidable on the column 21 and carries a lug 26 having attached thereto the ends of a chain 27 serving as a transmission member for a motor 28 to raise and lower the rock drill along the column 21. The chain 27 is trained over rollers or sprockets 29 at the extremities of the column and is looped over a sprocket 30 in a casing 31 on the rearward side of the column 21 within convenient reach of an attendant standing upon the surface supporting the mounting.

The casing 31 may be secured to the column in any well known manner and contains anti-friction bearings 32 for a shaft 33 in the sprocket

30. The shaft 33 has keyed thereto a worm wheel 34 between the bearings 32 that meshes with a worm 35 constituting an element of a train of gears serving to transmit motion from the motor

5 28 to the worm wheel 34. The intermeshing portions of the worm 35 and the worm wheel 34 have a non-locking pitch so that the pull of the rock drill on the chain during the downward movement of the rock drill will cause the worm 10 wheel 34 to rotate the worm 35, and on one end of the worm 35 is a gear 36 that meshes with a pinion 37 keyed to a shaft 38 which is supported by anti-friction bearings 39 in the casing 31. The shaft 38 has an end 40 in splined engagement with the crank shaft 41 of the motor

15 28 which is of the reversible, multi-piston type, only one piston 42 of which is shown for reciprocation in a cylinder 43 and having a rod 44 connected to the crank shaft 41.

20 The distribution of pressure fluid to the pistons 42 is effected by a rotary valve 45 which lies coaxial with the shaft 38 and has a stem 19 that extends into a recess 18 in a web 17 of the crank shaft. The stem 19 may be secured to, 25 or interlocked with, the web 17 in any suitable manner, and in the valve 45 is a passage 46 to register in successive order with the inlet passages 47 of the cylinders 43. The valve 45 also has a discharge passage 48 to register successively with the passages 47 and constantly with an atmospheric port 49 in the motor casing for exhausting the fluid from the cylinders 43.

25 The supply of pressure fluid is conveyed to the motor by a conduit 50, and communication between the conduit 50 and the distributing valve 45 is controlled by a throttle valve 51 adjacent the rotary valve 45. The throttle valve is shown as being of the rotary type having a lever 52, 30 whereby it may be manipulated, and has a central chamber 53 into which pressure fluid constantly flows from the conduit 50 through an arcuate groove 54 and a port 55, both in the throttle valve 51.

35 The arcuate groove is in constant communication with the conduit 50 in the various controlling positions of the throttle valve 51, and in the intermediate portion of the throttle valve is a port 56 to register, in one position of the throttle valve, with a passage 57 leading to the distributing valve 45 for communication with the passage 46 to cause the motor 28 to rotate in one direction and, in another position of the throttle valve 51, to register with a similar passage 58 through which pressure fluid is supplied to the

passage 46 for operating the motor in the opposite direction.

In accordance with the practice of the invention, means are provided for controlling the descending or feeding movement of the rock drill 22 at a rate best suited to maintain the correct operative relationship of the rock drill with respect to its working implement 59 which is attached, in a suitable manner, to the reciprocatory element of the rock drill. To this end the driving mechanism of the feeding device is provided with brake means designated, in general, by 60 and comprising a brake shoe 61 reciprocable in a cavity 62 in the casing 31 and having a surface 63 to cooperate with a facing of braking material 64 on the end surface of the gear 36. The brake shoe 61 is urged in the direction of the braking material 64 by springs 65 abutting the brake shoe 61 at one end and seating at their other ends against an adjusting plate 66 which, together with the brake shoe 61, is held against rotary movement within the cavity 62 by a key 67 seated in the casing 31.

A suitable space exists between the brake shoe 61 and the plate 66 to permit of axial movement of the brake shoe and of adjustment of the plate for varying the force of the springs 65 and, consequently, the pressure of the brake shoe against the braking material 64. Such adjustment is effected by manually operable means comprising a screw 68 having a key portion 69 for interlocking engagement with a slot 70 in the adjacent side of the plate 66. The screw 68 is threaded into the inner end of a plug 71 rotatable in an end wall 72 of the casing 31. Both the screw 68 and the plug 71 are coaxial with the plate 66 and on the outer end 73 of the plug 71 is a lever 74 to rotate the plug 71 for extending and retracting the screw 68.

The arrangement of the parts within the cavity 62 constituting the braking device is such that the springs 65 constantly tend to press the brake shoe against the braking material 64, and means are accordingly provided to release the brake, as when lifting the rock drill along the column 21 for removing the working implement 59 from the drill hole or to move the rock drill away from the working implement for the addition of an extension to the working implement in the event that a sectional working implement is being used. To this end a plunger 75 is arranged slidably within the worm 35 to engage, at one end, the brake shoe 61.

On the other end of the plunger is a head 76 that lies within a cavity 77 in the casing 31 and engages a diaphragm 78 that is clamped at its marginal portion between the casing 31 and a cover 79 that cooperates with the diaphragm 78 to define a chamber 80 for pressure fluid serving to actuate the plunger 75. Such pressure fluid is conveyed to the chamber 80 by a flexible conduit 81 having an end attached to the cover 79 and having the other end attached to the portion of the motor casing housing the valves 45 and 51 to communicate with a passage 82 in the motor casing controlled by the throttle valve 51.

The valve 51 is accordingly provided with a pair of ports 83 and 84 that communicate with the chamber 53 and are arranged in such wise that one of them will be placed in communication with the passage 82 for supplying pressure fluid to the chamber 80 in either of the positions which the throttle valve 51 occupies for valving pressure fluid to the passages 57 and

58. In the outer surface of the throttle valve, between the ports 83 and 84, is a groove 85 to afford communication between the passage 82 and the atmosphere for exhausting the fluid from the chamber 80.

In practice, and with the rock drill 22 in operation, the throttle valve 51 occupies a neutral position wherein the passages 57—58 and the ports 83—84 are blanked off. In this position of the 10 throttle valve the groove 85 registers with the passage 82 so that the chamber 80 will be open to the atmosphere and the rod 75 will release the brake shoe 61, which will then be free to move into engagement with the braking material 64 to 15 control the descending movement of the rock drill 22 at the desired rate. Whenever it is desired to move the rock drill upwardly along the column 21 the throttle valve 51 is rotated to bring the required ports and passages of the throttle valve and the motor casing into communication with each other for rotation of the motor 28 in the required direction, as for example, by placing the port 56 in registry with the passage 57.

In this position of the throttle valve the port 25 83 registers with the passage 82 and pressure fluid will enter the chamber 80 simultaneously with the admission of pressure fluid to the motor. The pressure fluid in the chamber 80 will shift the plunger 75 and thereby move the brake shoe 30 61 out of engagement with the braking material 64 to release the train of gearing for free operation.

After the rock drill has been retracted to the desired position the throttle valve 51 is returned to its neutral position to cut-off the supply of pressure fluid to the motor and to exhaust the fluid from the chamber 80 to the atmosphere, thereby, permitting the springs 65 to again return the brake shoe to its braking position. In 40 the event that, as adjusted, the springs 65 exert an insufficient pressure to hold the rock drill stationary, their force may be conveniently increased by merely rotating the lever 74 to actuate the plate 66 and further compress the springs.

45 Whenever it is intended to lower the rock drill by operation of the motor, the throttle valve 51 is rotated to bring the port 56 into communication with the passage 58 thereby supplying pressure fluid to the valve 45 for distribution to 50 the motor 28. In this position of the throttle valve the port 84 will communicate with the passage 82 and pressure fluid will flow into the chamber 80 for releasing the brake simultaneously with the admission of pressure fluid to the motor.

55 As will be readily apparent from the foregoing description, the application and release of the brake to and from the gear train are effected entirely by the throttle valve serving to control the feeding motor, and in such wise as to obviate the 60 need of shifting the throttle valve to positions other than those required for operating the motor. The braking effect of the brake 60 may, moreover, be conveniently and expeditiously varied to assure a feeding speed for the rock drill 65 suitable for the material being drilled by merely manipulating the lever 74 to vary the pressure of the springs 65.

I claim:

1. In a rock drill feeding device, the combination of a guide member and a rock drill slidably thereon, a flexible member on the guide member connected to the rock drill, a motor for driving the flexible member to lift the rock drill along the guide member for retracting the rock drill 70 from a drill hole, a gear train for transmitting mo-

tion from the motor to the flexible member, a brake for the gear train frictionally engaging one of the gears of said train to control the descending movement of the rock drill along the guide member, fluid actuated means for actuating the brake, and a valve for controlling the supply of pressure fluid to the motor and to the fluid actuated means.

2. In a rock drill feeding device, the combination of a guide member and a rock drill slidably thereon, a flexible member on the guide member connected to the rock drill, a motor for driving the flexible member to lift the rock drill along the guide member for retracting the rock drill from a drill hole, a gear train for transmitting motion from the motor to the flexible member, a spring-pressed brake constantly tending to apply braking force to the gear train, manually operable adjusting means for selectively varying the braking force of the brake, a fluid actuated piston for moving the brake out of braking position, and a valve for controlling the supply of pressure fluid to the motor and to the piston.

3. In a rock drill feeding device, the combination of a guide member and a rock drill slidable thereon, a flexible member on the guide member connected to the rock drill, a motor for driving the flexible member to lift the rock drill along the guide member for retracting the rock drill from a drill hole, a gear train for transmitting

motion from the motor to the flexible member, a brake for engagement with one of the gears of the train, springs constantly tending to press the brake into braking engagement with said one gear, means comprising a rotary plug and a screw in threaded engagement therewith for selectively varying the pressure of the springs against the brake, a lever on the plug for rotating said plug to advance and retract the screw, a fluid actuated piston, a rod extending slidably through the gear piston for transmitting movement from the piston to the brake for moving the brake out of braking position, and a valve for controlling the supply of pressure fluid to the motor and to the piston.
